(57) **CLAIM**

We claim the ornamental design for a tilt bin handle, as shown and described.

DESCRIPTION

FIG. 1 is a front perspective view of a tilt bin handle, showing our new design;

FIG. 2 is a front elevational view thereof;

FIG. 3 is a right side elevational view thereof; and

FIG. 4 is a top plan view thereof;

FIG. 5 is a left side elevational view thereof;

FIG. 6 is a rear elevational view thereof; and,

FIG. 7 is a bottom plan view thereof.

The broken lines showing a container are for the purposes of illustrating environment and form no part of the claimed design.
